OWEN H. SPENCER, OF INDIANAPOLIS, INDIANA, ASSIGNOR TO LINK-BELT COMPANY,
OF CHICAGO, ILLINOIS, A CORPORATION OF ILLINOIS.

STACKER FOR SILENT-CHAIN LINKS.

1,256,942.

Specification of Letters Patent. Patented Feb. 19, 1918.

Application filed April 24, 1916. Serial No. 93,322.

To all whom it may concern:

Be it known that I, OWEN H. SPENCER, a citizen of the United States, residing at Indianapolis, in the county of Marion and 5 State of Indiana, have invented a new and useful Stacker for Silent-Chain Links, of which the following is a specification.

In the manufacture of silent chain links, it is necessary that the links be operated on 10 individually a number of times in order to produce the finished chain. Heretofore it has been necessary in practice to place the individual links in position by hand for each operation, involving great labor and 15 expense, as the links are manufactured and handled by the million.

The present invention is one of a series, having the ultimate object of automatically bringing the links into position to be operated on, and has for its particular object the 20 transferring of a series of links from an end-to-end arrangement with their points all in the same direction to a side-by-side arrangement so that the points and the pitch 25 holes or pivot pin holes in all the links register, and placing the links in this latter position on a conveyer which will carry them in such position and arrangement to the desired place.

30 The mechanism for bringing the links from a haphazard mass to an end-to-end arrangement with the points all pointing in the same direction forms the subject-matter of other inventions; and the conveyer or 35 slide rail on to which the links are placed by my present invention forms, *per se*, the subject-matter of a co-pending application of Frank J. Oakes, Ser. No. 93,326, of even filing date herewith. My present invention 40 relates to the intermediate mechanism, for stacking the links in a side-by-side arrangement, and to the combination thereof with the supply chute which feeds it and the conveyer which it feeds. The links may be 45 fed in the initial end-to-end arrangement referred to to certain machines for treating the links, usually individually; or may be and usually are fed in such arrangement to a device such as that forming the subject-

50 matter of the present application or that forming part of the subject-matter of the co-pending application of Henry E. Hayward Ser. No. 93,321, of even filing date herewith, by which this initial link arrange-

ment, with the links arranged all in the same 55 position end to end, is transformed to a second arrangement or stack of links, with the links arranged side by side with their 60 points registering. This second arrangement or stack is found to be a most convenient 65 and suitable one for transporting the links from one place to another, as on the slide rail shown in the Oakes application above referred to, and for handling the links in 70 other machines which may operate on them, either individually, or in the assembling of 75 the complete chain, as for instance those shown in the co-pending applications of Frank J. Oakes and Owen H. Spencer, Ser. Nos. 93,324 and 93,325, also of even filing 80 date herewith. The various inventions covered by these several applications may be used together in different arrangements in 85 the manufacture of silent chains. It has been found that the initial arrangement of 90 links in an end-to-end relationship with the links all in the same position and with their 95 points all toward the same side is probably the most convenient and efficient starting point for getting the links into the second arrangement, or stack, with the links side by side with their points and crotches all registering; and that this second arrangement or stack is probably the most convenient and efficient arrangement for the handling of the links throughout the subsequent operations on them and in the assembling of the chain.

The accompanying drawings illustrate my invention. Figure 1 is a front face view of a 90 stacker embodying my invention in its preferred form; Fig. 2 is a section on the line 2—2 of Fig. 1; Fig. 3 is a partial section on the line 3—3 of Fig. 1; Fig. 4 is a front face view of a somewhat simpler form of 95 stacker; Fig. 5 is a section on the line 5—5 of Fig. 4; and Fig. 6 is a section on the line 6—6 of Fig. 5.

The links 10 are supplied in any suitable manner in an end-to-end arrangement with 100 their points all in the same direction, to the upper end of a vertical chute 11, which is open at the front, as clear from Figs. 1 and 4, and near its lower end is preferably bent forward so that it is slightly oblique, 105 as clear from Fig. 5. This chute is of such size that it holds the links in this end-to-end arrangement without overlapping but with

sufficient clearance for sliding. The chute 11 at its extreme lower end discharges tangentially into a circular chute 12 which is in the same plane as the lower oblique part 5 of the chute 11 and the center of which is preferably to that side of the chute 11 toward which the points of the links 10 are directed, so that the link points are toward the inside of such circular chute 12. The 10 links travel around this circular chute approximately 270°, until they come to the highest point thereof, at which point there is a hole 13 through the back or supporting face of said circular chute, which hole is of 15 proper size and shape to allow the passage of a single link through it with the link remaining parallel to the plane of the chute 12. At this hole, the points of the link are downward, and the hole registers properly 20 with a slide rail 14 of general inverted T-shape so that a link which passes through the hole 13 passes on to and astride of the slide rail 14. The receiving end of this slide rail is conveniently of such slope that the 25 link slides along it by gravity, as clear from Fig. 5, and is perpendicular to the plane of the circular chute 12. The lower end of the slide rail 14 may be horizontal, and may be provided with a stop 15 against which 30 the links 10 pile up. The slide rail *per se* is the invention of Frank J. Oakes, and is set forth in detail in his aforesaid co-pending application.

The links 10 are carried around in the 35 circular chute 12 by a toothed wheel 20 pivoted to turn in the plane of such circular chute about the center thereof. The wheel 20 is provided with a number of teeth 21 which are properly spaced apart so as to 40 project into the crotches 22 of the links 10 as said links are fed into the circular chute 12 from the chute 11, the projecting portions of these teeth 21 being shaped to correspond in general to the shape of the crotch 22, and 45 being different for different shapes of links, as illustrated in Figs. 1 and 4. These teeth 21 hold the successive links 10 at slight distances apart, instead of allowing them to abut as they do in the chute 11. If desired, 50 the wheel 20 may have a second set of teeth 23, usually narrower than the teeth 21, which teeth alternate with the teeth 21 and project between adjacent links 10 in the circular chute 12. These teeth 23 are desirable, but 55 are not absolutely necessary, and are provided in the wheel 20 shown in Fig. 1 but not in the wheel 20 shown in Fig. 4. The advancing edges 24 of the teeth 21, and also of the teeth 23 when such teeth are provided, 60 are beveled, as clear from Figs. 2, 5, and 6, so that such edges are further advanced toward the front face of the wheel than toward the rear face. This causes these beveled edges 24 to act as cams on the links 10 65 to hold the links firmly against the rear

faces of the circular chute 12, and when the hole 13 is reached to force the links through such hole on to the slide rail 14.

In order to prevent the links 10 from being carried past the hole 13, a stop 25 is 70 provided on the side of such hole opposite that from which the links 10 are fed to it, as shown in Figs. 1, 2, 4, and 5. This stop may have its working face at right angles to the plane of the circular chute 12, as 75 shown by the face 26 in Figs. 4 and 6, in which case the force of gravity and the cam action of the faces 24 are wholly relied on for forcing the links through the hole 13, or may be oblique to such plane, as is the 80 face 27 in the arrangement shown in Figs. 1 and 2, projecting farther toward the advancing link at the front than at the rear, so that it also acts as a cam to assist the force of gravity and the cam faces 24 in 85 forcing the link through the hole 13 on to the slide rail 14. If desired, the stop 25 may be adjustable, by being mounted on a slide 28 which is forced to the left (Fig. 1) by a spring 29 but may be moved to the 90 right against the action of such spring by a screw 30.

Preferably, in order to minimize friction and prevent catching of the links, the opening 13 is made considerably larger throughout the greater part of the ends and back of the link than is the link which is to slide through it, but is provided with inwardly projecting ribs 31 (Fig. 1) which project in so as to bear against the edges 100 of the link and thus guide it with a minimum of friction. These ridges 31 are so located that they avoid those places on the link edges where burs are liable to exist.

The links 10 are preferably partly exposed 105 through the front face of the chutes 11 and 12, as clear from Figs. 1 and 4. The front faces of the link points when in the circular chute 12 are covered by an outwardly projecting flange 32 on the wheel 20, which flange lies just in front of the plane of the links themselves. The front faces of the links near their backs are covered by an inwardly projecting flange, which may be held permanently in place as in the arrangement shown in Fig. 4, or may be formed by a removable ring 33 seated in a pocket 34, so that by the removal of such ring, as indicated in dotted lines in Fig. 1, access is given 110 to the links in the chute 12 and if necessary links may be removed from or placed in such chute.

In operation, links 10 are supplied in an end-to-end arrangement and with their 115 points all in the same direction to the upper end of the chute 11. These links slide down the chute 11 in this end-to-end arrangement and pass tangentially into the circular chute 12 at the left (Figs. 1 and 4). The teeth 21 of the wheel 20 pass up into the respective 120

130

crotches of the links, and the teeth 23 when provided pass between adjacent links, thus separating the links slightly one from another. The weight of the links in the chute 11 furnishes the motive force which forces the links down along such chute and around into the circular chute 12, and which turns the wheel 20 in the direction of the arrow. This force is transferred from the link 10 just passing from the chute 11 into the chute 12 to the teeth 21 and 23 and therefrom to the wheel 20, which acts through other teeth 21 and 23 to carry other links in the circular chute 12 around the latter, so that the links 10 in the right hand half of the circular chute 20 (Figs. 1 and 4) lie back against the teeth 21 and 23 by reason of gravity and friction and are propelled forward by such teeth as the wheel 20 turns. The movement of the parts stops when the weight of the links 10 in the chute 11 falls below a certain value, which is required to overcome the friction of the parts. As the links 10 are carried around by the teeth 21 and 23, they come successively opposite the hole 13, through which they are forced on to the slide rail 14 by the cam faces 24 and the cam face 27, assisted by gravity. The links slide down the slide rail 14 and stack up in a side-by-side arrangement at the lower end thereof.

I claim as my invention:

1. In combination, a chute for receiving silent chain links in an end-to-end arrangement with the link points all pointing in the same direction, a circular chute into which said first chute discharges substantially tangentially and having its center on that side of the first chute toward which the link points are directed, said circular chute having an opening for allowing a link to slide from said circular chute out of the plane of the latter, and a slide rail in position to receive astride it links which slide through said opening.
2. In combination, a chute for receiving crotched links in an end-to-end arrangement, a circular chute into which said first chute discharges substantially tangentially, said circular chute having an opening for allowing a link to slide from said circular chute out of the plane of the latter, and a slide rail in position to receive astride it links which slide through said opening.
3. In combination, a chute for receiving silent chain links in an end-to-end arrangement with the link points all pointing in the same direction, a circular chute into which said first chute discharges substantially tangentially and having its center on that side of the first chute toward which the link points are directed, said circular chute having an opening for allowing a link to slide from said circular chute out of the plane of the latter, a slide rail in position to receive astride it links which slide through said opening.
4. In combination, a chute for receiving silent chain links in an end-to-end arrangement with the link points all pointing in the same direction, a circular chute into which said first chute discharges substantially tangentially and having its center on that side of the first chute toward which the link points are directed, said circular chute having an opening for allowing a link to slide from said circular chute out of the plane of the latter, a slide rail in position to receive astride it links which slide through said opening, and a wheel pivoted at the center of said circular chute and having teeth projecting into said circular chute for engaging the links in said chute, said teeth being tapered so as to act as cams to force the links through said opening.
5. In combination, a chute for receiving crotched links in an end-to-end arrangement, a circular chute into which said first chute discharges substantially tangentially, said circular chute having an opening for allowing a link to slide from said circular chute out of the plane of the latter, a slide rail in position to receive astride it links which slide through said opening, and a wheel pivoted at the center of said circular chute and having teeth projecting into said circular chute for engaging the links in said chute, said teeth being tapered so as to act as cams to force the links through said opening.
6. In combination, a chute for receiving crotched links in an end-to-end arrangement, a circular chute into which said first chute discharges substantially tangentially, said circular chute having an opening for allowing a link to slide from said circular chute out of the plane of the latter, a slide rail in position to receive astride it links which slide through said opening, and a wheel pivoted at the center of said circular chute and having teeth projecting into said circular chute for engaging the links in said chute.
7. In combination, a chute for receiving crotched links in an end-to-end arrangement, a circular chute into which said first chute discharges substantially tangentially, said circular chute having an opening for allowing a link to slide from said circular chute out of the plane of the latter, a slide rail in position to receive astride it links which slide through said opening, and a wheel pivoted at the center of said circular chute and having teeth projecting into said circular chute for engaging the links in said chute, said teeth projecting into the crotches of the links.
8. In combination, a chute for receiving crotched links in an end-to-end arrangement,

a circular chute into which said first chute
discharges substantially tangentially, said
circular chute having an opening for allow-
ing a link to slide from said circular chute
5 out of the plane of the latter, a slide rail in
position to receive astride it links which
slide through said opening, and a wheel piv-
oted at the center of said circular chute and
having teeth projecting into said circular
10 chute for engaging the links in said chute,
said teeth projecting between adjacent links
so as to space them apart.

9. In combination, a chute for receiving crotched links in an end-to-end arrangement, a circular chute into which said first chute discharges substantially tangentially, said circular chute having an opening for allowing a link to slide from said circular chute out of the plane of the latter, a slide rail in position to receive astride it links which slide through said opening, and a wheel pivoted at the center of said circular chute and having teeth projecting into said circular chute for engaging the links in said chute, alternate teeth projecting into the crotches of the links and between adjacent links.
- 15
- 20
- 25

links.

10. In combination, a chute for receiving crotched links in an end-to-end arrangement, a circular chute into which said first chute discharges substantially tangentially, said circular chute having an opening for allowing a link to slide from said circular chute out of the plane of the latter, a slide rail in position to receive astride it links which slide through said opening, and a wheel pivoted at the center of said circular chute and having teeth projecting into said circular chute for engaging the links in said chute, said teeth projecting into the crotches of the links, said teeth being tapered so as to act as cams to force the links through said opening.

11. In combination, a chute for receiving
45 crotched links in an end-to-end arrange-
ment, a circular chute into which said first
chute discharges substantially tangentially,
said circular chute having an opening for al-
lowing a link to slide from said circular
50 chute out of the plane of the latter, a slide
rail in position to receive astride it links
which slide through said opening, and a
wheel pivoted at the center of said circular
chute and having teeth projecting into said
55 circular chute for engaging the links in said
chute, said teeth projecting between adjacent
links so as to space them apart, said teeth
being tapered so as to act as cams to force
the links through said opening.

60 12. In combination, a chute for receiving
crotched links in an end-to-end arrangement,
a circular chute into which said said first
chute discharges substantially tangentially,
said circular chute having an opening for
65 allowing a link to slide from said circular

chute out of the plane of the latter, a slide rail in position to receive astride it links which slide through said opening, and a wheel pivoted at the center of said circular chute and having teeth projecting into 70 said circular chute for engaging the links in said chute, alternate teeth projecting into the crotches of the links and between adjacent links, said teeth being tapered so as to act as cams to force the links through said 75 opening.

13. In combination, a chute for receiving crotched links in an end-to-end arrangement, a circular chute into which said first chute discharges substantially tangentially, said 80 circular chute having an opening for allowing a link to slide from said circular chute out of the plane of the latter, a slide rail in position to receive astride it links which slide through said opening, and a stop for 85 preventing said links from moving in said circular chute beyond said opening, said stop having a beveled face which serves as a cam to force the links through said opening. 90

14. In combination, a chute for receiving crotched links in an end-to-end arrangement, a circular chute into which said first chute discharges substantially tangentially, said circular chute having an opening for allowing a link to slide from said circular chute out of the plane of the latter, a slide rail in position to receive astride it links which slide through said opening, and a stop for preventing said links from moving in said circular chute beyond said opening. 95 100

15. In combination, a chute for receiving crotched links in an end-to-end arrangement, a circular chute into which said first chute discharges substantially tangentially, said 105 circular chute having an opening for allowing a link to slide from said circular chute out of the plane of the latter, a slide rail in position to receive astride it links which slide through said opening, a wheel pivoted at the 110 center of said circular chute and having teeth projecting into said circular chute for engaging the links in said chute, and a stop for preventing said links from moving in said circular chute beyond said opening, 115 said stop having a beveled face which serves as a cam to force the links through said opening.

16. In combination, a chute for receiving crotched links in an end-to-end arrangement, a circular chute into which said first chute 120 discharges substantially tangentially, said circular chute having an opening for allowing a link to slide from said circular chute out of the plane of the latter, a slide rail in 125 position to receive astride it links which slide through said opening, a wheel pivoted at the center of said circular chute and having teeth projecting into said circular chute for engaging the links in said chute, and a 130

stop for preventing said links from moving in said circular chute beyond said opening.

17. In combination, a chute for receiving crotched links in an end-to-end arrangement, 5 a circular chute into which said first chute discharges substantially tangentially, said circular chute having an opening for allowing a link to slide from said circular chute out of the plane of the latter, a slide rail in 10 position to receive astride it links which slide through said opening, a wheel pivoted at the center of said circular chute and having teeth projecting into said circular chute for engaging the links in said chute, said teeth 15 being tapered so as to act as cams to force the links through said opening, and a stop for preventing said links from moving in said circular chute beyond said opening, said stop having a beveled working face which 20 serves as a cam which co-operates with the beveled faces of the teeth to force the links through said opening.

18. In combination, a chute for receiving crotched links in an end-to-end arrangement, 25 a circular chute into which said first chute discharges substantially tangentially, said circular chute having an opening for allowing a link to slide from said circular chute out of the plane of the latter, a slide rail in 30 position to receive astride it links which slide through said opening, a wheel pivoted at the center of said circular chute and having teeth projecting into said circular chute for engaging the links in said chute, said 35 teeth being tapered so as to act as cams to force the links through said opening, and a stop for preventing said links from moving in said circular chute beyond said opening.

19. In combination, a chute for crotched 40 links in an end-to-end arrangement, said chute having a lateral opening for allowing links to slide from said chute out of the plane of the latter, and a slide rail in position to receive astride it links which slide 45 through said lateral opening.

20. In combination, a chute for crotched links in an end-to-end arrangement, said chute having a lateral opening for allowing links to slide from said chute out of the 50 plane of the latter, a slide rail in position to receive astride it links which slide through said lateral opening, and a stop for preventing said links from moving in said chute beyond said opening, said stop having 55 a beveled working face which serves as a cam to force the links through said opening.

21. In combination, a chute for crotched links in an end-to-end arrangement, said chute having a lateral opening for allowing 60 links to slide from said chute out of the plane of the latter, a slide rail in position to receive astride it links which slide through said lateral opening, and a stop for preventing said links from moving in said chute be- 65 yond said opening.

22. In combination, a chute for crotched links in an end-to-end arrangement, said chute having an opening for allowing links to slide out of it, a conveyer for receiving in side-by-side arrangement links discharged 70 from said opening, and a spacing device for holding spaced from a link at such opening the other links in the chute.

23. In combination, a chute for crotched links in an end-to-end arrangement, said 75 chute having an opening for allowing links to slide out of it, a conveyer for receiving in side-by-side arrangement links discharged from said opening, a spacing device for holding spaced from a link at such opening the 80 other links in the chute, and a stop for preventing said links from moving in said chute beyond said opening, said stop having a beveled working face which serves as a cam to force the links through said opening. 85

24. In combination, a chute for crotched links in an end-to-end arrangement, said chute having an opening for allowing links to slide out of it, a conveyer for receiving in side-by-side arrangement links discharged 90 from said opening, a spacing device for holding spaced from a link at such opening the other links in the chute, and a stop for preventing said links from moving in said chute beyond said opening.

25. In combination, a support for holding crotched links in end-to-end relationship, a support for holding said links in side-by-side arrangement, said first support being arranged to discharge links singly on to said 100 second support, and a spacing device for holding spaced from a link about to be discharged from said first support the other links on said first support.

26. In combination, a support for holding 105 crotched links in end-to-end relationship, a support for holding said links in side-by-side arrangement, discharge mechanism for receiving links from said first support and depositing them on said second support, and 110 a spacing device for holding spaced from a link about to be discharged from said first support the other links on said first support.

27. In combination, a chute for receiving flat members in edge-to-edge relationship, 115 and a conveyer for receiving said flat members in side-by-side relationship, said chute being provided with a lateral opening for permitting the flat members reaching it to be discharged therethrough out of the plane 120 of the chute, and said conveyer being arranged to receive in side-by-side relationship the flat members discharged through said opening.

28. In combination, a chute for receiving 125 flat members in edge-to-edge relationship, a conveyer for receiving said flat members in side-by-side relationship, said chute being provided with a lateral opening for permitting the flat members reaching it to be dis- 130

charged therethrough out of the plane of the chute, and said conveyer being arranged to receive in side-by-side relationship the flat members discharged through said opening, and a spacing device for holding spaced from the flat member about to be discharged through said opening the other flat members in said chute.

29. In combination, a chute for receiving flat members in edge-to-edge relationship, a conveyer for receiving said flat members in side-by-side relationship, said chute being provided with a lateral opening for permitting the flat members reaching it to be discharged therethrough out of the plane of the chute, and said conveyer being arranged to receive in side-by-side relationship the flat members discharged through said opening, said chute near said opening being arc-shaped, and a wheel provided with teeth projecting into said chute to engage the flat members therein for carrying them along said chute to said opening.

30. In combination, a chute for receiving flat members in edge-to-edge relationship, a conveyer for receiving said flat members in side-by-side relationship, said chute being provided with a lateral opening for permitting the flat members reaching it to be discharged therethrough out of the plane of the chute, and said conveyer being arranged to receive in side-by-side relationship the flat members discharged through said opening, said chute near said opening being arc-shaped, and a wheel provided with teeth projecting into said chute to engage the flat members therein for carrying them along said chute to said opening, said teeth holding spaced from one another the flat members which they engage.

31. In combination, a chute for receiving flat members in edge-to-edge relationship, a conveyer for receiving said flat members in side-by-side relationship, said chute being provided with a lateral opening for permitting the flat members reaching it to be discharged therethrough out of the plane of the chute, and said conveyer being arranged to receive in side-by-side relationship the flat members discharged through said opening, said chute near said opening being arc-shaped, and a wheel provided with teeth projecting into said chute to engage the flat members therein for carrying them along said chute to said opening, the forward faces of said teeth being tapered to act as cams tending to force said flat members through said opening when it is reached.

32. In combination, a chute for receiving flat members in edge-to-edge relationship, a conveyer for receiving said flat members in side-by-side relationship, said chute being provided with a lateral opening for permitting the flat members reaching it to be discharged therethrough out of the plane of the

chute, and said conveyer being arranged to receive in side-by-side relationship the flat members discharged through said opening, and a stop for engaging said flat members when they reach said opening and preventing them from traveling past said opening. 70

33. In combination, a chute for receiving flat members in edge-to-edge relationship, a conveyer for receiving said flat members in side-by-side relationship, said chute being provided with a lateral opening for permitting the flat members reaching it to be discharged therethrough out of the plane of the chute, and said conveyer being arranged to receive in side-by-side relationship the flat members discharged through said opening, and a stop for engaging said flat members when they reach said opening and preventing them from traveling past said opening, said stop being tapered so that it acts as a cam to force through said opening the flat members which engage it. 80

34. In combination, a chute for receiving crotched links in an end-to-end arrangement, a circular chute into which said first chute discharges substantially tangentially, said circular chute having an opening for allowing a link to slide from said circular chute out of the plane of the latter, a slide rail in position to receive astride it links which slide through said opening, and a wheel pivoted at the center of said circular chute and having teeth projecting into said circular chute for engaging the links in said chute, said wheel being so arranged that it is operated by the weight of the links in the chutes. 90

35. In combination, a chute for receiving crotched links in an end-to-end arrangement, a circular chute into which said first chute discharges substantially tangentially, said circular chute having an opening for allowing a link to slide from said circular chute out of the plane of the latter, a slide rail in position to receive astride it links which slide through said opening, and a wheel pivoted at the center of said circular chute and having teeth projecting into said circular chute for engaging the links in said chute, said teeth being tapered so as to act as cams to force the links through said opening, said wheel being so arranged that it is operated by the weight of the links in the chutes. 105

36. In combination, a chute for receiving crotched links in an end-to-end arrangement, a circular chute into which said first chute discharges substantially tangentially, said circular chute having an opening for allowing a link to slide from said circular chute out of the plane of the latter, a slide rail in position to receive astride it links which slide through said opening, a wheel pivoted at the center of said circular chute and having teeth projecting into said circular chute 110

125

130

for engaging the links in said chute, and a stop for preventing said links from moving in said circular chute beyond said opening, said wheel being so arranged that it is 5 operated by the weight of the links in the chutes.

37. In combination, a chute for receiving crotched links in an end - to - end arrangement, a circular chute into which said first 10 chute discharges substantially tangentially, said circular chute having an opening for allowing a link to slide from said circular chute out of the plane of the latter, a slide rail in position to receive astride it links 15 which slide through said opening, a wheel pivoted at the center of said circular chute and having teeth projecting into said circular chute for engaging the links in said chute, and a stop for preventing said links 20 from moving in said circular chute beyond said opening, said stop having a beveled face which serves as a cam to force the links through said opening, said wheel being so arranged that it is operated by the weight 25 of the links in the chutes.

38. In combination, a chute for crotched links in an end-to-end arrangement, said chute having a lateral opening for allowing links to slide from said chute out of the 30 plane of the latter, and a slide rail in position to receive astride it links which slide

through said lateral opening, said chute being arranged so that the links slide along it and through said opening by gravity.

39. In combination, a chute for receiving 35 flat members in edge-to-edge relationship, a conveyer for receiving said flat members in side-by-side relationship, and means operated by the weight of the links in said chute for receiving said flat members from said 40 chute and depositing them on said conveyer.

40. In combination, a chute for receiving flat members in edge-to-edge relationship, and a conveyer for receiving said flat members in side-by-side relationship, said chute 45 being provided with a lateral opening for permitting the flat members reaching it to be discharged therethrough out of the plane of the chute, and said conveyer being arranged to receive in side-by-side relationship the flat members discharged through said opening, said chute and said conveyer being arranged so that the flat members are moved along said chute and through said opening on to said conveyer by the action of 50 gravity on said flat members.

In witness whereof, I have hereunto set my hand at Indianapolis, Indiana, this 21st day of April, A. D. one thousand nine hundred and sixteen.

OWEN H. SPENCER.
